UNITED STATES PATENT OFFICE.

VICTOR W. ZILEN, OF CHATTANOOGA, TENNESSEE, ASSIGNOR TO LUCEY MANUFACTURING CORPORATION, OF NEW YORK, N. Y., A CORPORATION OF TENNESSEE.

ROTARY DRIVE MECHANISM.

Application filed August 26, 1921. Serial No. 495,615.

To all whom it may concern:

Be it known that I, VICTOR W. ZILEN, a citizen of the United States, residing at Chattanooga, in the county of Hamilton and State of Tennessee, have invented certain new and useful Improvements in Rotary Drive Mechanism; and I do hereby declare the following to be a full, clear, and exact description of the same, reference being had 10 to the accompanying drawings, forming part of this specification.

This invention relates to a rotary drive mechanism for use in the rotary drilling of oil wells and has for its principal object the provision of mechanism to transmit power 15 from the source of power to the rotary table without the use of idlers, such idlers adding considerable lost motion and resulting in unnecessary wear and tear on the derrick structure.

A further object of the invention is to provide mechanism in which the resultant of the driving forces is at a point near the ground level so that the vibrations in the structure 20 will be reduced to a minimum.

A further object of the present invention is to provide some means to enable the engineer to rigidly connect the prime mover to the base which carries the drive shaft, such 25 means in the drawings being illustrated as lugs or flanges carried by the sills, corresponding lugs or flanges on the engine base and distance pieces between the lugs, held in place preferably by bolts extending from 30 lug to lug.

A still further and important object of the invention lies in the elimination of chains from the power transmitting mechanism between the primary shaft and the rotary table 40 and in the convenient and accessible location of the various necessary shafts, such as the hoisting drum shaft and the auxiliary or capstan shaft.

In the rotary system, a vertical drill pipe, 45 carrying at its lower end a cutting bit, is secured to the horizontal rotary table in such manner as to cause the drill pipe to rotate with the table, the latter being so mounted as to provide free rotation. Hoisting mechanism, usually located to one side of the derrick and generally secured to the derrick frame, raises and lowers the drill pipe as 50 necessary during the progress of the drilling.

In the ordinary form of driving mechanism of this type a sprocket wheel is placed on the shaft of the hoist and a driving chain is run downward from the line shaft located on the framing of the hoist and from this shaft a driving chain is run either directly 60 across the derrick to a sprocket wheel secured to the rotary table, or to a sprocket wheel on the secondary shaft located outside the derrick frame. In the latter case, this secondary shaft then drives a horizontal jack 65 shaft set at right angles thereto by means of bevel gearing, and the rotary shaft which drives the rotary table is connected to the horizontal jack shaft by means of a pair of universal joints.

With either of the systems above mentioned the primary shaft or line shaft is set in bearings on the posts which also support the hoisting drum, these posts being set on the top of the derrick side sill and extending 70 upward to a point where they are joined to the horizontal frame members of the derrick, so forming a part thereof. A sprocket wheel carried by the primary shaft receives a driving chain leading from the prime mover 75 which, as before mentioned, is on a lower level.

The location of the primary shaft is, therefore, not only uncomfortably high above the machinery which it drives, but its 80 location tends to cause undue vibration in the derrick frame and in the mechanism carried thereby. Then too, the tendency is to loosen the engine from its foundation and also to pull down the derrick, and the 85 vibratory forces intensified by the action of the driving chain from the line shaft set up a violent oscillation of the entire derrick structure and in the machinery carried by it so that it is not at all an infrequent happening that the drive chains break and whip 90 around the derrick, and the tendency to movement of the engine base necessitates not only a heavy foundation but also requires an extra heavy bracing against the 100 derrick, the sum of these actions consequently endangering the lives of the men working in and about the derrick, reducing the efficiency of the machinery, and lowering the factor of safety of the materials 105 used.

In the system of gearing illustrated in the present disclosure the primary shaft is in-

terposed between the prime mover and the hoisting drum and is at a low level. The auxiliary shaft which carries the "catheads", as the small capstans are almost universally called in this art, is located above the other shafts, but it should be remembered that only a small amount of power is transmitted to this shaft, as these small drums or capstans are only used for the convenience of 5 the workmen in handling slight loads. It will also be noted from the following description that the derrick floor is entirely clear except on the side where the single shaft runs from the bevel gearing to the 10 rotary, and that all chains are removed from the center of drilling operations, hence reducing to a minimum, if not entirely eliminating danger from the whipping of the 15 chains.

20 In the drawings,—

Figure 1 is a plan view of a preferred form of my device;

Fig. 2 is a side elevation thereof partly in section; Fig. 2^a (same sheet) is a continuation of the side elevation showing particularly the prime mover and its connection to the sills of the derrick; and

Fig. 3 is a vertical section taken on the line 3—3 of Fig. 2.

30 The rotary table 10 is mounted upon a suitable base 11 which is securely fastened to the timber supporting the derrick floor 12. The drill pipe carrying at its lower end a cutting bit is not shown as it forms no 35 part of the present invention, but the drill stem 14 to which it is secured is shown in Fig. 1. The rotary table is provided on the lower face of its overhanging edge with bevel teeth 15 preferably shrouded, and 40 adapted to mesh with a bevel pinion 16 secured to the rotary shaft 17 mounted in bearings 18 in a casting 19 supported on skids 20 extending inward from sills 21. At a point between the two bearings 18, the 45 shaft 17 is provided with a hexagonal or squared section 22 for convenience in turning the shaft with a wrench when so desired and at its free end this shaft 17 carries one fork of the universal joint 23, the other 50 fork being carried by a short section 24. A clamp coupling 25 connects this short steel shaft 24 to a similar shaft 26 forming part of the universal joint 28 by which the shaft 26 is connected to the drive shaft 29 mounted in bearings 30 on the bed or casting 31 secured to the longitudinal sills 33 as shown.

The primary shaft 35 is mounted in bearings 36 and 37 carried by the outward extending arms of the bed 31.

60 The primary shaft 35 receives power from the engine 40 by means of the drive chain 41 which engages a sprocket wheel 43 keyed to the shaft 35 at about its center and adjacent the bearing 36. The engine base 42 is 65 spaced from the sills 33 by distance pieces

44 engaging lugs or flanges 48 and 49 on the base 42 and sills 33, respectively. A bevel gear 45 is loosely mounted adjacent the opposite bearing 37 and meshes with a pinion 46 carried by the shaft 29, which shaft is 70 put in motion by shifting the jaw clutch 47 splined to the shaft 35 so as to engage the bevel gear 45 and lock same to the constantly revolving shaft 35.

The drum shaft 50 is mounted in journal 75 boxes 51 secured to the uprights 39 and carries a drum 53 of the usual type having wide flanges 54, each preferably engaging a brake band operated by a crank arm 55 upturned at one end to form a handle lever 56. This 80 drum shaft 50 carries a pair of loose sprocket wheels 58 and 59 adapted to be locked to the lever operated jaw clutches 60 and 61, respectively, so as to drive the drum at a slow or fast speed as may be desired, the 85 slow speed sprocket 58 being connected to a sprocket wheel 62 on the primary shaft by means of a chain 63 and the more rapid drive being accomplished through a chain 64 joining the sprocket wheel 59 to a sprocket 90 wheel 65 keyed to the primary shaft on the outside of the journal box 37, the last mentioned sprocket wheel being preferably of somewhat larger diameter than the sprocket 95 wheel 62 used for the slow drive.

In addition to the above mechanism there is provided an auxiliary shaft 72 rotating in bearings 73 secured to the uprights 39 on the opposite side from the bearings 51 and at a somewhat higher elevation. At either 100 end of this shaft is permanently secured a cathead 74 and at the appropriate point on the shaft a sprocket 75 is keyed, this sprocket being connected by a chain 76 with the cooperating sprocket wheel 77 loosely mounted on the primary shaft 35 and controlled by a clutch 79 splined to the primary shaft and controlled by a small hand lever 105 not shown, or any other convenient mechanism.

The operation of the device is believed to be apparent from the foregoing description, the prime mover which may be a motor, steam engine or any other source of power drives the shaft 35 by means of the chain 115 41 and sprocket wheel 43. The power thus transmitted to the primary shaft is transmitted to the rotary table 10 through the coaxial shafts 29, 26, 24 and 17; to the drum shaft 50 through the sprocket wheel 62 or 120 65 depending upon the speed desired; and to the auxiliary or cathead shaft 72 by means of the sprocket wheel 75. It will be noted that the primary shaft 35 is constantly driven since the sprocket wheel 43 125 is keyed thereto, as are also the sprocket wheels for driving the drum shaft. The two sprocket wheels, however, on the drum shaft are both loosely mounted and the clutches which control them are both 130 lo-

cated on the drum shaft, whereas the clutch for controlling the operation of the auxiliary shaft is splined to the primary shaft itself so that the cathead shaft is normally 5 inoperative, but all of these mechanisms are so constructed as to be independently operable.

What I claim is:

1. In a drive mechanism for a well drilling rotary drive, a primary shaft, a rotary table, shafting, a bevel pinion on either end thereof, a bevel gear on said primary shaft meshing with one of said pinions, a bevel gear carried by said rotary table for meshing with the other of said pinions, a clutch on said primary shaft for controlling the operation of said first-mentioned bevel gear, a drum shaft parallel to said primary shaft and located at a higher level than said primary shaft, gearing connecting said primary shaft, and said drum shaft, a clutch mounted on said drum shaft for rendering inoperative the drum shaft driving mechanism an auxiliary shaft parallel to said drum shaft and said primary shaft, gearing connecting said primary shaft and said auxiliary shaft, and a clutch mechanism car-

ried by said primary shaft for rendering inoperative said auxiliary shaft driving mechanism.

2. In a rotary drive mechanism, a primary shaft, a prime mover, power transmitting mechanism connecting said prime mover and said primary shaft, a rotary table, a sectional shaft transmitting power from said primary shaft to said rotary table, a bed providing bearings for said sectional shaft and for said primary shaft, a clutch mechanism mounted on said primary shaft between said bearings for rendering said sectional shaft inoperative, an auxiliary shaft, catheads on said auxiliary shaft, means for driving said auxiliary shaft from said primary shaft, a drum shaft, mounted at a level substantially between said primary shaft and said auxiliary shaft, a drum on said shaft, a plurality of independent means for transmitting motion from said primary shaft to said drum shaft, and means carried by said drum shaft for rendering inoperative either or both of said means.

VICTOR W. ZILEN.
